STRUCTURAL STEEL DERRICK

John Hart Wilson, Wichita Falls, Tex.

Application February 19, 1938, Serial No. 191,523

4 Claims. (Cl. 189—16)

The present invention relates to structural steel masts and to methods of and apparatus for fabricating and erecting such masts.

It has heretofore been generally the practice in the erection of structural steel masts of various types, and particularly in the erection of masts of the type commonly designated oil field derricks, to transport the various structural members to the point at which the mast is to be erected and to there assemble the members together, piece by piece, the bottom members being first positioned and secured, and the upper members being successively added piece by piece until the mast or derrick has been completed.

Many of these derricks are of substantial height and there is a considerable element of danger to the structural workers engaged in their erection. Likewise, by reason of the fact that each structural worker must devote a large part of his effort to maintain his working position, when elevated a substantial distance above ground, his effectiveness in assembling the various individual structural units in final position is decreased, the worker, in the average case, finding it necessary to use one hand in maintaining his position, leaving available one hand only to work with, thus increasing the cost and decreasing the speed of erection.

In accordance with the present invention a structural steel derrick of novel construction is provided, together with a novel method of assembly, the purpose being to lower the cost of erection of such a structure, safeguard the structural workers engaged in such erection, and to greatly decrease the time necessarily expended in the erection of a derrick of any given height and cross-sectional dimensions.

The invention contemplates the assembling together of the various structural units of which the derrick is composed at the point where the derrick is to be erected but, as distinguished from the prior methods of derrick erection above previously referred to, the derrick is built in two or more elongated sections which lie recumbent on the ground during fabrication and these sections are subsequently erected in a novel manner and rigidly secured together, the resulting derrick being even more rigid when finally completed than one of the same dimensions constructed in the manner heretofore employed. Also the derrick is so put together that it may be readily disassembled when its usefulness at the spot of its erection is over. Substantial savings as well as increased safety are realized, therefore, both in

the erection and in the dismantling of the derrick.

As will be apparent to one skilled in the art, the novel derrick and method of erecting it may be modified in various respects in the erection of masts of different types intended for use for different specific purposes. That form of derrick which is illustrated in the accompanying drawings, therefore, is set forth by way of example only.

In the drawings:

Figure 1 is a side view showing in full lines the derrick sections just prior to erection and in dotted lines the completed and assembled derrick, the means by which the erection is accomplished being also shown in full lines;

Figure 2 is a top plan view of the disassembled derrick and erecting means;

Figure 3 is a section on line 3—3 of Figure 1, although on a larger scale;

Figure 4 is a side elevation of the upper portion of a raising or erecting mast, which comprises a portion of the erecting means for the main structure;

Figure 5 is a side elevation, upon a larger scale, of the upper end of the completed derrick;

Figure 6 is a side elevation of a detail, showing the means for the attachment of the derrick sections;

Figure 7 is a section on line 7—7 of Figure 1; and

Figure 8 is a section on line 8—8 of Figure 6.

The erected derrick shown in dotted lines in Figure 1 of the drawings is of the type made use of in large numbers throughout the oil fields, and commonly designated an oil field derrick. The invention, however, may be employed in the erection of structural steel masts of other types and designs and the details of construction of which vary materially from the details of the construction of the well-known oil field derrick. In every instance, however, the derrick will be fabricated in sections, the sections being disposed horizontally and each comprising a longitudinally rigid truss-like structure which, when erected into vertical position, will comprise a portion of the completed derrick, being secured to other similarly constructed and erected portions.

In the practice of the invention it is preferred that a base or platform, indicated at 10 in the drawings, be first built or constructed at the point where the derrick is to be erected. The details of construction of the base may be varied at will to suit circumstances but it should be of rather sub-

stantial character and firmly anchored and supported, since it will subsequently bear the entire weight of the completed derrick, also the weight of the smaller erecting mast, and eventually the weight of any apparatus mounted upon the completed derrick, such as for instance oil well drilling and casing pulling mechanism.

Two pairs of hinge elements are indicated at 11, the axes of the hinge pins of each pair being 10 in alignment and the axes of the two pairs being parallel. The truss members which together eventually comprise the erected derrick are indicated at 12 and 13 respectively and it will be perceived that the adjacent ends of these truss 15 members are connected to the hinges 11 so that, when the truss members are moved from the positions in which they are shown in full lines in Figure 1 to the positions in which they are shown in dotted lines, they rock or swing about the parallel 20 axes of the two sets of hinges.

The details of construction of the several truss members may be varied widely and it is only necessary that they shall be longitudinally rigid so as not to materially deflect while being swung 25 upwardly into erect position about the hinges at their lower ends. Each truss is actually erected or constructed while horizontally disposed, the trusses being in alignment with each other. Assembling the various structural members in the 30 fabrication of each truss may be most conveniently done inasmuch as much of the work involved in the bolting or otherwise fastening of the structural members together may be done by workers standing upon the ground. At the most 35 short ladders are required and these are used only when the derrick is of such size that each individual truss component of the same has, when lying horizontally, a substantial height. It is of course necessary, in constructing longitudinally 40 rigid truss members, to provide each with both upper and lower longitudinal chords in order that the requisite stiffness may be obtained, as will be readily understood by those familiar with the construction of trusses. In general, however, 45 the trusses may be constructed of any suitable elements and in any desired manner it being only essential to provide each with upper chords 12' and 13', each having an offset 14, for purposes to be hereinafter described.

50 A raising mast or column is indicated at 15, this mast being relatively small in cross-section as compared with the cross-section of the derrick, the lower end of this mast being suitably mounted upon the platform 10 intermediate the pairs of 55 hinges 11. The raising mast is provided at its top with a cross beam 16 to the outer ends of which are secured the downwardly and outwardly extending anchoring cables 17, the lower ends of which are secured to anchoring devices 18 embedded 60 in the ground so that the top of the raising mast 15 is securely braced and maintained thereby in fixed position. Also mounted upon the raising mast, at the top thereof, are pulleys or sheaves 20 and adjacent the bottom, pulleys or sheaves 21. Elevating cables 22 extend from suitable winches or cable winding mechanisms (not shown) over the platform 10, passing around anti-friction rollers 23, thence around pulleys 21, and upwardly through the raising mast to and over pulleys 20. These cables extend in opposite directions from pulleys 20, one extending downwardly to the derrick section 12 and the others extending downwardly to the derrick section 13, the lower ends of these cables being connected to 70

the derrick sections at intermediate points, as indicated in Figures 1 and 2.

After completion of the two truss-like structures 12 and 13 shown, and after erection of the raising mast 15 and attachment of the cables 22, 5 traction may be applied simultaneously to these cables with the result that the two derrick portions 12 and 13 are simultaneously rocked about their pivoted lower ends into erect or vertical position, as shown in dotted lines in Figure 1, 10 in which position the corresponding inner longitudinal chords of the two truss portions of the derrick are in contact. When so positioned, the derrick sections are detachably secured together and in Figures 5, 6 and 8 certain details of construction of the derrick, including the attachment 15 means, are shown.

Thus the adjacent chords of the derrick sections, which are brought into contact when the raising operation is completed, preferably comprise angle bars 25, the corresponding flanges of which are in contact and in parallel relationship when the raising operation has been completed. Aligned cylindrical bores or apertures 26 are formed in the contacting angle sections and 25 through each pair of aligned apertures a bolt 27 is projected, nuts being applied to tie the angle members together by means of the bolt. There may be as many of these securing bolts as is necessary to firmly and rigidly attach the derrick 30 sections together into a single unitary structure. The securing devices may all be subsequently detached in the event that it is desired to disassemble the derrick and to lower its sections to the ground by reversing the operation of erection. 35

As it is necessary that the beam 16 secured to the top of the raising mast 15 shall have such length that its ends lie without the derrick when completely assembled, in order that the anchoring ropes may be clear, the chords 12' and 13' of 40 the derrick sections 12 and 13 are provided with the reentrant angles 14 or offsets previously referred to, in order that these sections shall not strike the beam 16 when erected. In Figure 3 of the drawings the ends of beam 16 are shown 45 to protrude through the apertures in the derrick provided for the purpose, the offsets 14 registering to provide such apertures. After the derrick has been erected in the manner specified and the bolts 27 or other securing devices applied, 50 the raising cables are removed, likewise the anchoring cables 17. The raising mast may then be taken down, section by section, or moved into one corner of the derrick, out of the way, but nevertheless in readiness to be repositioned when 55 the derrick is to be dismantled.

Having thus described the invention, what is claimed as new and desired to be secured by Letters Patent is:

1. In combination, a base, a vertical raising 60 mast having its lower end detachably secured to the base centrally thereof, a horizontal beam mounted upon the upper end of said raising mast, supporting cables extending downwardly and outwardly from the outer ends of said beam 65 to anchoring elements, whereby said raising mast is secured in position, means associated with the base for pivotally supporting the adjacent ends of horizontally disposed elongated trusses, and cables extending from the top of the raising mast 70 to said trusses respectively whereby said trusses may be simultaneously rocked upwardly about said means, said trusses being longer than the raising mast and having recesses to receive said beam when erected.

2. A structural steel derrick comprising two identical elongated longitudinally rigid truss-like structures, each such structure having two longitudinal members adapted to be brought into engagement with the corresponding members of the other structure, and means for detachably securing said members together in pairs, the respective members of each said pair being formed with registering recesses.
- 10 3. A structural steel derrick mounted on a base and comprising upright and bracing members defining a vertically extending hollow structure having an opening extending transversely therethrough at a substantial distance from said base, 5 said derrick being longitudinally separable into sections, a raising and lowering mast extending upward from said base and enclosed within said hollow structure, said mast having a horizontal beam at its upper end, the ends of said beam projecting outwardly through said opening, and supporting cables extending from the ends of said beam to anchoring elements.
- 15 4. The method of fabricating and erecting a structural steel derrick which comprises separately fabricating two rigid truss-like structures 20 each to form one-half of the completed derrick, horizontally aligning said structures with adjacent ends spaced apart, pivotally attaching such adjacent ends to fixed members, erecting a vertical raising mast intermediate said fixed members, 25 said mast being of a height less than that of said derrick when erected and having a horizontal beam secured at the upper end thereof and extending at right angles to the center line of said structures, supporting said mast in position by cables extending from each end of said beam to anchoring points disposed laterally of said respective structures, simultaneously drawing said structures into vertical position by means of cables connecting each to the top of the raising mast, each said structure moving between said cables which extend to points disposed laterally of said respective structures, and securing said structures together in abutting relation, said structures being formed with mating recesses in 20 their abutting portions to provide clearance for said beam, whereby said derrick when erected wholly encloses said mast and beam except the outer ends of the latter.

JOHN HART WILSON. 25
